UNITED STATES PATENT OFFICE.

JOHN W. HASBURG, OF CHICAGO, ILLINOIS.

MARKING GAGE OR TRAM.

1,028,720.

Specification of Letters Patent.

Patented June 4, 1912.

Application filed January 27, 1912. Serial No. 673,717.

To all whom it may concern:

Be it known that I, JOHN W. HASBURG, a citizen of the United States, residing at Chicago, in the county of Cook and State 5 of Illinois, have invented certain new and useful Improvements in Marking Gages or Trams, of which the following is a specification.

My invention relates to improvements in 10 marking gage or tram.

One of the objects of my invention is to provide a convenient simple tool especially adapted for use of china or ceramic decorators.

15 Other and further objects will become apparent to persons skilled in the art from a consideration of the following description taken in conjunction with the drawings wherein:—

20 Figure 1 is an elevation of the device; Fig. 2 is a plan view thereof; Fig. 3 is an enlarged broken-away part of the device in vertical section; and, Fig. 4 is a similar view showing a pin or pointed tool in the 25 chuck.

In all of the views the same reference characters are used to designate similar parts.

The beam or bar 5 is slotted at one end, as 30 at 6, said slot terminating in a bore 7 thereby to render the prongs 8 and 9 more resili- 35 ent. The bifurcated end is tapered and screw threaded, as at 10, thereby forming one element of a chuck. A head 11 is cor- 40 respondingly tapered and threaded at 12, so that when the head is screwed on to the ends of the bar 5 the prongs 8 and 9 are drawn closer together. Between the bore 7 and the ends of the prongs is another bore 45 13. A split tube 14 neatly fits the bore 13 and may contain a pencil lead 15 or other marker. The marker 15 fits neatly into the split tube 14 and is adjustable vertically therein when the head 11 is not screwed up 50 to its fullest extent upon the prongs 8 and 9.

The head is bored centrally, as at 16 to receive a scribe or pin 17. The pin may be

passed through the head 11 and into the slot 6 so that when the head is screwed up on the prongs the pin 17 will be held in a 50 central position and its inwardly projecting end will be clamped between the prongs 8 and 9, as shown in Fig. 4. In this case the marker may be removed from the split tube 14 so as to permit greater latitude and freer 55 movement of the prongs 8 and 9 to better clamp the pin 17.

When the split tube 14 is within the bore and the chuck head 11 is screwed tight on the end of the bar 5 the prongs are drawn 60 toward each other, thereby contracting the split tube and clamping the marker 15 tightly therein at any selected vertical position.

A head 20, provided with a point 21 is 65 perforated, as at 22, and is slideable along the bar 5 and may be fixed in position by the set screw 23.

By means of my improved tool the center of a dish or other disk may be quickly ob- 70 tained; marginal boundaries may be readily defined and circles may be described, while the prick-point 7 may be used for various purposes.

What I claim is:

75 A tool of the class described comprising a bar tapered and screw threaded at one end and bifurcated by a slot at said end, said slot terminating in a bore larger in diameter than the slot, a split tube for holding a 80 marker, said bar having another bore in said slotted end parallel with the first said bore, and a tapered, screw-threaded head having a tapered screw-threaded perforation for engagement with the threaded end of 85 said bar and a smaller central perforation for insertion of a scribe pin.

In testimony whereof I hereunto set my hand in the presence of two witnesses.

JOHN W. HASBURG.

In the presence of—

W. LINN ALLEN,
MARY F. ALLEN.
